UNITED STATES PATENT OFFICE.

WILLIAM FRANCIS MAY, OF THORNTON HEATH, ENGLAND, ASSIGNOR OF ONE-HALF
TO JAMES ADAMS KEENE, OF LONDON, ENGLAND.

LUNCHEON OR PICNIC BOX OR CASE.

Application filed August 20, 1926, Serial No. 130,375, and in Great Britain July 23, 1926.

This invention relates to luncheon or picnic boxes or cases and comprises a box formed of hinged members which can be opened out so that the box or case is convertible into a kind of table upon which the contents of the box or case can be arranged for serving a meal.

In a suitable construction according to the invention, the body of the box or case is made in sections hinged together so that when opened out or extended, together with the lid, a series of the surfaces thereof are brought into one plane to form a table with legs or supports therefor. For example, the body of the box or case is made in two equal parts by dividing vertically two opposite sides on central lines, the members of these divided sides subsequently acting as supports for the table. The other sides of the said body are hinged along their lower edges to opposite edges of the bottom of the box or case, whilst to the upper edge of one of the said sides is hinged the lid of the box or case, the edges of the lid at right angles to that furnished with the hinge or hinges being provided with flat extensions at right angles to the lid which also subsequently act as supports for the table. These extensions fit into corresponding recesses in the divided sides of the body when the lid is closed so that the exterior surfaces of the extensions are flush with those of the said divided sides, the unrecessed portions of the sections of the divided sides being preferably rebated at their meeting edges so that they form closed joints. The sides, bottom and lid are so hinged together that when the box or case is opened out these members are butted together at their adjacent edges with their exterior surfaces in a common plane to form the table top, the divided sides of the body and the right-angled extensions of the lid forming the supports for the said table.

Suitable fastenings are provided to secure the parts together when in the box form.

To enable the invention to be fully understood I will describe it by reference to the accompanying drawing in which:

Figure 1 is a perspective view of a luncheon or picnic box or case constructed in accordance with the invention.

Figure 2 is a similar view to figure 1, but showing the lid open.

Figure 3 is a perspective view of the box or case fully opened out or extended and

Figure 4 is a view similar to Figure 3, showing the extended box or case turned over to form a table.

a, Figures 1 and 2, is the upright body of the box or case having the four sides **b**, **b**¹, **c**, **c** and **d** and **e** are, respectively, the bottom and lid of the said box or case. The body **a** is made in two equal parts by dividing the sides **c**, **c** vertically and centrally at **f** into two equal sections **c**¹, **c**² which subsequently act as supports when the box is extended to form a table, as indicated in Figure 4, whilst the sides **b**, **b**¹ are hinged respectively by **g**, **g**¹ to the bottom **d**. The lid **e** is hinged by a hinge **h** to the upper edge of one of the sides **b**¹. **i**, **i** are the two flat extensions on the edges of the lid at right angles to that furnished with the hinge **h** and which also subsequently serve as supports for the table when the box is extended to form a table and **j**, **j** indicate where the sections **c**¹, **c**² of the sides **c** are recessed to receive the extensions **i**, **i** when the lid is closed, as indicated in Figure 1, so that the exterior surfaces of the said sides and of the said extensions are flush. **c**³, **c**³ Figure 3 and 4, indicate the rebates when I prefer to form in the meeting edges of the unrecessed portions of the sections **c**¹, **c**² of the divided sides to form closed joints. **k**, **l** are hook and eye fastenings for securing the two parts of the body together and **m**, **m** are spring lever fastenings or locks for securing the lid **e** to the body. **n** is a handle on the lid to enable the box or case to be easily carried, the said handle being hinged to the said lid and turning down and fitting into a recess **n**¹ in the lid so that it lies flush with the surface of the said lid when not required for use.

By the described construction it will be seen that assuming the box or case to be closed as indicated in Figure 1, by unfastening the lid **e** from the body **a** by manipulating the fastenings **m**, **m** and turning it on its hinge **h** into the position indicated in Figure 2 where it is in the same plane as the side **b**¹ with the edges carrying the said hinge abutting, and then unfastening the hooks **k** from the eyes **l**, the parts of the box or case can be extended, as indicated in Figure 3, so that the bottom **d** and side **b** align with said side **b**¹ and lid **e**, with the

edges carrying the hinges g and g' abutting. By turning the extended box or case upside down, it can then serve as a table, as indicated in Figure 4, the parts c^1 , c^2 and i acting as supports or legs therefor.

I claim:

1. A luncheon or picnic box or case comprising a series of sections including two pairs of parallel sections, said sections being hinged together so that their exterior surfaces can be brought into one plane to form a table, a plurality of said sections being provided at opposite ends with perpendicular sections rigidly secured thereto, and depending equal distances therefrom when said hinged sections are arranged in a plane, and forming the only supports for the table, said perpendicular sections having meeting edges and forming the remaining opposite sides of the box or case when in closed position.

2. A luncheon or picnic box or case comprising a series of sections including two pairs of parallel sections, said sections being hinged together so that their exterior surfaces can be brought into one plane to form a table, a plurality of said sections being provided at opposite ends with perpendicular sections rigidly secured thereto, and depending equal distances therefrom when said hinged sections are arranged in a plane, and forming the only supports for the table, said perpendicular sections having meeting edges and forming the remaining opposite sides of the box or case when in closed position, said perpendicular sections at each end of the hinged sections being provided with overlapping portions adjacent to their meeting edges to form closed joints, and having their exterior faces in the same plane.

3. A luncheon or picnic box or case comprising parallel side sections, a bottom section, and a top section hinged together in series so that their surfaces can be brought into one plane to form a table, the parallel side sections being each provided at each end with perpendicular end sections rigidly connected therewith and of equal transverse width, said perpendicular end sections having meeting edges and forming the ends of the box or case, one of the other hinged sections being provided with a perpendicular section at each end of the same width, as the previously mentioned perpendicular sections, the outer edges of the last mentioned perpendicular section being adapted to meet edges of the first mentioned perpendicular

section perpendicular to the meeting edges thereof, all of said perpendicular sections at each end of the box or face having their outer edges in the same plane, said perpendicular sections forming the sole support for the hinged section when in open position for use as a table.

4. A luncheon or picnic box or case comprising parallel side sections, a bottom section, and a top section hinged together in series so that their surfaces can be brought into one plane to form a table, the parallel side sections being each provided at each end with perpendicular end sections rigidly connected therewith and of equal transverse width, said perpendicular end sections having rebated meeting edges, and having recessed portions adjacent to the top of the box, said hinged top sections being provided at each end with a perpendicular end section of the same width as the first mentioned end sections to engage the recessed portions of the first mentioned end sections, all of said perpendicular sections at each end of the box or case having their outer edges in the same plane, said perpendicular sections forming the sole support for the hinged sections when in open position for use as a table.

5. A luncheon or picnic box or case comprising parallel side sections, a bottom section, and a top section hinged together in series so that their surfaces can be brought into one plane to form a table, the parallel side sections being each provided at each end with perpendicular end sections rigidly connected therewith and of equal transverse width, said perpendicular end sections having rebated meeting edges, and having recessed portions adjacent to the top of the box, said hinged top sections being provided at each end with a perpendicular end section of the same width as the first mentioned end sections to engage the recessed portions of the first mentioned end sections, all of said perpendicular sections at each end of the box or case having their outer edges in the same plane, said perpendicular sections forming the sole support for the hinged sections when in open position for use as a table, and locking means for connecting the end sections of the top to the recessed end sections connected with the side section remote from the hinged edge of the top section, to hold the box or case in closed position.

WILLIAM FRANCIS MAY.
